(74) Attorney, Agent, or Firm—Schweitzer Cornman Gross
& Bondell LLP(57) CLAIM

We claim the ornamental design for a bottle, as shown and described.

DESCRIPTION

FIG. 1 is a front perspective view;

FIG. 2 is a plan view thereof;

FIG. 3 is a side elevational view thereof;

FIG. 4 is a front elevational view thereof; and,

FIG. 5 is a bottom plan view thereof.

The broken line shown in FIG. 5 is for environmental purposes only and forms no part of the claimed design.
